FLEXIBLE DIAPHRAGM FOR FUEL PUMPS AND THE LIKE AND METHOD OF FORMING THE SAME

Howard L. Asp, Evanston, and Paul T. Haake, Park Ridge, Ill., assignors to Crane Packing Company, Chicago, Ill., a corporation of Illinois

Application January 2, 1953, Serial No. 329,382

5 Claims. (Cl. 137—793)

The present invention relates to flexible diaphragms and more particularly to a diaphragm of the type which has a central body portion which moves in a direction transversely of the general plane of the diaphragm and relative of the peripheral portion thereof. The invention is also concerned with a novel method of forming such diaphragms.

Diaphragms of the type outlined above will be found useful in connection with fuel pumps for automotive or Diesel use, as well as in connection with a large variety of other instrumentalities which depend for their operation upon the use of a flexible member of this character. Among such instrumentalities are pressure regulators which are employed for controlling a flow of a liquid or gaseous medium from a high pressure area to a low pressure area; valve constructions; airbrake mechanisms; pressure operated electrical circuit making and breaking apparatus, and many other constructions or assemblies where the flexible member is generally known under the general characterizing term of "pump diaphragm" regardless of whether it is primarily designed for use in connection with a pump or only in a generally related manner.

Diaphragms constructed in accordance with the principles of the present invention contemplate the employment as an essential part thereof, if not as the entire diaphragm, a suitable flexible impervious material or compound which will satisfy all of the requirements of a pump diaphragm, particularly with respect to flexibility.

Among the compounds contemplated as a base material for construction of the present diaphragm is a polytetrafluoroethylene polymer manufactured by E. I. du Pont de Nemours & Company under the trade-name "Teflon". This material is characterized by its chemical inertness through a range of temperatures extending from extremely low temperatures up to approximately 570° F. "Teflon" is insoluble in all known chemicals and no reaction has been noted with any chemicals including the most destructive type such as the halogenated hydro-carbons, chlorosulfonic acid acetyl chloride, boron trifluoride and other high boiling point solvents at their boiling points.

Such chemical inertness of "Teflon" would ordinarily point the way toward its ideal use as a pump diaphragm for fuel pumps or for other hydraulic devices such as valves, particularly where oils or corrosive acids are encountered. However, while this material has adequate toughness, and is possessed of good tensile strength, as well as of excellent abrasive and frictional qualities, it lacks the resiliency necessary to insure ease of flexing when employed as a diaphragm, particularly at the thicknesses demanded by the ordinary engineering exigencies of fairly large installations.

The present invention is designed to overcome the above noted physical limitations that are attendant upon the use of "Teflon" as a diaphragm material, as well as upon other materials which are rendered unfit for such use by virtue of their inability to flex freely. Toward this end, the invention contemplates the provision of a novel diaphragm, preferably formed entirely of "Teflon" which

2

is so constructed as to have relatively movable central and peripheral regions which are connected together by a multi-layer intermediate ring-like area or portion of greater flexibility than the remaining portions of the diaphragm and in which the layers thereof are capable of independent flexing so as to greatly increase the sensitivity of the diaphragm as a whole.

The diaphragm, in one form thereof is formed of a single piece of the "Teflon" or other material with solid 10 relatively movable inner central and outer peripheral regions respectively, connected together by the intermediate multi-layer flexible region. In another form, the diaphragm is of similar design with strips of foil or other separator material interposed between the layers of the 15 intermediate region. In yet another form of the invention the diaphragm may have a solid central region and the remainder thereof, including the peripheral region, may be laminated.

In each of the above contemplated forms of the diaphragm, different methods of manufacture may be resorted to and, among these methods, at least one of them is regarded as being novel and within the scope of the present invention.

The provision of a flexible diaphragm of the character 25 briefly outlined above being among the principal objects of the present invention, other objects and advantages will become more readily apparent as the following description ensues.

In the accompanying single sheet of drawings forming 30 a part of this specification several embodiments of the invention have been shown. In these drawings:

Fig. 1 is a plan view of one form of the improved pump diaphragm constructed in accordance with the principles of the present invention. In this view, a sub-surface cut has been made in the front face of the diaphragm to more clearly reveal the nature of the invention.

Fig. 2 is a sectional view taken substantially along the line 2—2 of Fig. 1.

Figs. 3 and 4 are sectional views similar to Fig. 2 taken 40 through slightly modified forms of diaphragm.

Fig. 5 is a vertical sectional view, somewhat schematic in its representation, of a mold which may be employed to perform the final sealing step in the manufacture of the diaphragm of Fig. 1.

Fig. 6 is a sectional view similar to Fig. 5 showing a 45 mold which may be employed to perform the final sealing step in the manufacture of the diaphragm of Fig. 4 and

Fig. 7 is a fragmentary side elevational view, schematic in its representation, showing certain steps that are performed in the construction of the diaphragm illustrated 50 in Fig. 1.

Referring now to the drawings in detail and in particular to Figs. 1 and 2 wherein one form of flexible pump diaphragm constructed in accordance with the principles of the present invention has been shown. The diaphragm 55 is in the form of a single piece of flexible impervious material of circular disc-like configuration including a flat peripheral rim portion 10, a slightly offset central portion 12 and a frusto-conical connection portion 14 of wide taper. The offset portion 12 includes a solid hub 16 and the peripheral portion 11 is in the form of a solid ring of the material of which the diaphragm is formed, the hub 16 and rim 11 being integrally joined by separate layers or laminations 18 of the material. The diaphragm is provided with the usual central attachment hole 20 which 60 passes centrally through the hub 16 and the rim portion 11 is provided with the usual spaced bolt holes 22. It is to be noted that the medial laminated portion of the diaphragm extends from the peripheral edge of the hub 16 to and beyond a peripheral edge of the offset portion 12 and through the frusto-conical connection portion 14 to the inner edge of the solid rim portion 11.

In manufacturing diaphragms such as are shown in Figs. 1 and 2, a cylinder of the molded material is first provided in any suitable manner, as for example by a molding operation with an inside diameter equal to the diameter of the bolt hole 20 and with an outside diameter equal to the diametrical extent of the completed diaphragm. Such a cylinder is shown at 24 in Fig. 7. The cylinder is then mounted in a rotating chuck 26 and slicing operations are performed upon it to consecutively produce a series of the diaphragms. Utilizing a suitable cutter 28, the material of the cylinder is sliced inwardly adjacent the free end thereof to the periphery of the hub 16, the thickness of the slice being equal to the thickness of one of the laminations 18. The cutting tool is then withdrawn and additional slices are made in the cylinder until the requisite number of laminations 18 have been formed. The last slice made upon the cylinder to produce a single diaphragm is carried through the cylinder to completion so that a diaphragm blank such as the one shown at 29 in Figs. 5 and 7 is formed and separated from the remainder of the body portion of the cylinder. These slicing operations are repeated until the cylinder has been divided in its entirety into a number of the blanks 29. The severed units 29 are removed from the chuck 26 and the bolt holes 22 are formed therein in any suitable manner, as for example by a punching operation.

In order to seal the peripheral regions of the individual layers thus created in the marginal regions of each diaphragm blank, the blank is operated upon by a molding apparatus such as that shown in Fig. 5. This apparatus includes upper and lower dies 30 and 32 respectively, together with suitable means (not shown) for moving the dies relative to each other.

The upper die 30 includes a central section 34 and a concentric surrounding section 36, the two sections being separated by a heat insulating member 38 of tubular configuration. The lower die 32 is of similar design and includes a central section 40 and a concentric outer section 42 which is separated from the central section 40 by a tubular insulating member 44. The composite lower die 32 is provided with a shallow circular recess or depression 46 and the upper composite die 30 is provided with a cooperating circular protuberance 48, the depression 46 and protuberance 48 cooperating with each other to provide the offset portion 12 of the completed diaphragm as shown in Fig. 2. The die section 34 is provided with a centering hole 50 while the cooperating die section 40 is provided with a centering pin 52 in registry with the hole 50.

The outer upper and lower die sections 36 and 42 respectively are adapted to be heated in any suitable manner, as for example by conventional band heaters 54.

When the individual diaphragm blanks 24 are operated upon by the molding structure Fig. 5, it will be seen that the layers or laminations of the blank in the peripheral regions thereof will be heat sealed together to provide the peripheral ring portion 10 of the diaphragm shown in Fig. 2. The degree of heat employed and the pressure involved will, of course, vary to suit the requirements of these diaphragm materials and for purposes of illustrations utilizing Teflon as the material of the diaphragm, the sections 36 and 42 may be brought to a temperature of 750° F. or thereabouts and the pressure maintained for approximately 20 seconds, after which the mold sections may be separated and the completed diaphragm stripped therefrom.

Referring now to Fig. 3 it will be seen that the diaphragm illustrated therein is similar to that shown in Fig. 2. The principal difference is that the marginal region of the diaphragm is not heat sealed and the various laminations associated with the diaphragm remain free of each other in this marginal region. The diaphragm of Fig. 3 may be formed in a manner substantially identical with the formation of the diaphragm of Fig. 2 but in this latter form of diaphragm the heat sealing operation is

omitted so that the diaphragm exists as a completed article as soon as it has been severed from the Teflon cylinder 24. Utilizing similar reference numerals, the diaphragm of Fig. 3 thus consists of the solid central hub portion 16a and a series of outer surrounding separated layers 18a of the material which remain separated from the periphery of the hub portion 16a completely to the periphery of the diaphragm. For purposes of illustration, the various layers 18a at the right hand side of Fig. 3 have been spread outwardly to illustrate the fact that they are independent of each other in the peripheral regions of the diaphragm. It will, of course, be understood that in actual use the peripheral regions of the diaphragm will be clamped together by the bolting flanges of the particular pump or other structure with which the diaphragm may be associated.

In the form of the invention shown in Fig. 4, the diaphragm is comprised of a plurality of individual layers of material designated at 60, 62 and 64 respectively. These layers are heat sealed together to provide a central hub portion 16b which in effect constitutes a homogeneous central hub. The various layers 60, 62, and 64 are also heat sealed at their peripheral region to provide an outer rim portion 10b which in effect is uniformly solid, the two solid unbroken portions 16b and 19b being interconnected by the separated laminations 18b. If desired, relatively thin flat rings 68 of metal foil which may be of aluminum are interposed between the separated layers 18b. These rings do not detract from the flexibility of the diaphragm as a whole and they serve to effect sharp lines of division between the unsealed and heat-sealed portions of the diaphragm respectively. The metal foil rings 68, in addition to their separating function, also serve as anti-friction members which permit the various laminations or layers of the "Teflon" material to slide upon one another thus enhancing the flexibility of the medial regions of the diaphragm. Since the metal foil elements are relatively thin and yieldable, they cannot be regarded as reinforcing members and their true functions are as separators and anti-friction members as stated above.

In the formation of the diaphragm of Fig. 4, a molding apparatus such as has been illustrated in Fig. 6 is employed. This apparatus is similar to the apparatus shown in Fig. 5 and includes upper and lower die assemblies 80 and 81 respectively.

The upper die 80 includes a central section 82 and concentric outer ring-like sections 84 and 86. The central core section 82 is provided with a centering hole 88. The cooperating mating lower die 81 is similarly formed with a central section 90 and concentric surrounding ring sections 92 and 94. The core section 90 is provided with a centering pin 96 in registry with the centering hole 88.

The central core sections 82 and 90 are adapted to be heated in any suitable manner, as for example by surrounding band heaters 98 and the outer cooperating mold sections 86 and 94 are adapted to be similarly heated by band heaters 99 as shown. The intermediate cooperating mold sections 84 and 92 remain unheated. Insulating rings or cylinders 100 and 102 serve to separate the intermediate mold sections 84 and 92 from the central and outer sections 82, 86 and 90, 94 respectively.

The composite mold section 81 is provided with a shallow circular depression or recess 104 and the composite mold 80 is provided with a complementary circular protuberance 108, which recess and protuberance cooperate with each other to provide the offset intermediate region 12b of the completed diaphragm of Fig. 4. In the molding operation, the heated portions of the dies may be maintained at a temperature of 750° F. and the duration of the molding operation may be 20 seconds. It will be understood, however, that the duration of molding time and the degree of heat applied may be varied in accordance with the thickness of the

various layers to be heat sealed and in accordance with the combined thicknesses of these layers.

The invention is not to be limited to the exact arrangement of parts shown in the accompanying drawings or described in this specification, nor is it to be limited to the specific process described herein. Various changes in the details of construction and in the process involved may be resorted to without departing from the spirit of the invention. For example, while in each of the diaphragms shown, three layers or laminations are illustrated in the central regions of the diaphragm, it will be understood that a greater or lesser number of such laminations may be utilized if desired. Similarly, the temperatures and pressures referred to are only exemplary and for different sizes and shapes of diaphragms, as well as for diaphragms which are formed of different materials, these temperatures and pressures will be varied so as to produce the desired heat sealing of the laminations at the periphery and, if desired, in the central regions of the diaphragm. Only insofar as the invention has been particularly pointed out in the accompanying claims is the same to be limited.

What is claimed:

1. A flexible pump diaphragm of the character described comprising a unitary disc-like member of appropriate configuration and of a homogeneous flexible material including a solid unbroken central hub portion of predetermined uniform thickness, a solid unbroken continuous outer peripheral portion of the same predetermined uniform thickness, and an intermediate portion connecting said hub and peripheral portions, said intermediate portion comprising a plurality of layers of the homogeneous flexible material, each layer being in the form of an unbroken continuous flexible ring having its inner margin integrally joined to the periphery of said hub portion and its outer margin integrally joined to the inner margin of the outer peripheral portion, the opposite faces of said diaphragm being free of radial and circumferential seams and joints and presenting smooth unbroken surfaces, and a flat continuous ring-like member of metal foil interposed between the adjacent superimposed layers of the homogeneous flexible material and substantially filling the space existing therebetween.

2. A flexible pump diaphragm as defined in claim 1 in which the central hub portion and the outer peripheral portion are offset from each other and in which the layers of the intermediate portion are contained in part in the general plane of said hub portion.

3. A flexible pump diaphragm as defined in claim 1 in which the central hub portion and the outer peripheral

portion are offset from each other and are connected together by an inclined medial portion and in which the layers of the intermediate portion are wholly contained in the general plane of said hub portion and in the inclined medial portion.

4. The method of forming a series of flexible pump diaphragms from cylindrical flexible stock which comprises slitting the stock transversely inwardly from the cylindrical surface thereof along closely spaced parallel planes a predetermined distance to provide a series of ring-like layers of the material of the stock in the outer regions of the stock while leaving a solid central hub portion, and severing the thus partially formed diaphragms from each other by effecting a series of transverse cuts

15 completely through the stock between adjacent partially formed diaphragms.

5. The method of forming a series of flexible pump diaphragms from cylindrical flexible stock which comprises slitting the stock transversely inwardly from the cylindrical surface thereof along closely spaced parallel planes a predetermined distance to provide a series of ring-like layers of the material of the stock in the outer regions of the stock while leaving a solid central hub portion, severing the thus partially formed diaphragms from each other by effecting a series of transverse cuts

20 completely through the stock between adjacent partially formed diaphragms, and thereafter individually heat-sealing the peripheral regions of the diaphragms to secure the various layers thereof together.
